US00D671317S

(12) **United States Design Patent**
Sabounjian

(10) **Patent No.:** **US D671,317 S**
(45) **Date of Patent:** **** Nov. 27, 2012**

(54) **COLLAPSIBLE CONTAINER WITH POCKETS**

(75) Inventor: **Azad Sabounjian**, Irvine, CA (US)

(73) Assignee: **Pro-Mart Industries, Inc.**, Irvine, CA (US)

(**) Term: **14 Years**

(21) Appl. No.: **29/390,322**

(22) Filed: **Apr. 22, 2011**

(51) **LOC (9) Cl.** **03-01**

(52) **U.S. Cl.** **D3/285; D3/289**

(58) **Field of Classification Search** **D3/273, D3/276, 280, 283–293, 301, 300, 294; 190/100–127, 190/900–903; 150/106, 107, 108, 110, 111, 150/112, 118; 206/320**

(57) **CLAIM**

The ornamental design for a collapsible container with pockets, as shown and described.

DESCRIPTION

FIG. 1 is a perspective view of the container of this invention with a cover that is closed;

FIG. 2 is a top plan view of the container of FIG. 1;

FIG. 3 is a front elevation view of the container of FIG. 1, with the opposing rear side being a mirror image thereof;

FIG. 4 is a right side elevation view of the container of FIG. 1, with the opposing side view being a mirror image thereof;

FIG. 5 is a bottom plan view of the container of FIG. 1;

FIG. 6 is a perspective view of the container of FIG. 1 with the cover open;

FIG. 7 is a top plan view of the container of FIG. 6; and,

FIG. 8 is a sectional view taken along section 8-8 of FIG. 4.

The broken lines that are shown in FIGS. 1, 4 and 6 represent claimed stitching.

1 Claim, 5 Drawing Sheets
